SKI SLED

Nels Saari, Minneapolis, Minn.

Application October 4, 1939, Serial No. 297,825

11 Claims. (Cl. 280—12)

My present invention provides a ski sled in which standard skis are used as the runners. The skis are detachably connected in such a manner that they will run in parallel but can be simultaneously oscillated to steer the sled. The operator standing on the skis manipulates the connecting and steering mechanism to guide the sled. A novel means is provided for connecting and steering the sled by lateral tilting of the skis in the one direction or the other. The connecting and steering devices are detachable and adjustable so that, when desired, the skis can be disconnected and independently used with certain of the connections applied to each ski. The steering and connecting devices may be readily removed from the skis and the skis used in the ordinary way.

Generally stated, the invention consists of the novel devices, combination of devices and arrangement of parts hereinafter described and defined in the claims. In the accompanying drawings which illustrate the invention, like characters indicate like parts throughout the several views.

25 Referring to the drawings:

Fig. 1 is a view in perspective looking at the complete ski sled viewed from the front thereof, some parts being broken away and some parts being sectioned;

30 Fig. 2 is a rear elevation of the sled;

Fig. 3 is a detail in perspective showing certain important elements of the steering and connecting mechanism, some parts being broken away and some parts being shown in section;

35 Fig. 4 is a detail in section taken on the line 4—4 of Fig. 3;

Fig. 5 is a side elevation showing an intermediate part of one of the skis and portions of a post detachably but rigidly secured to and rising 40 from the ski;

Fig. 6 is a front elevation of the parts shown in Fig. 5, some parts being sectioned; and

Fig. 7 is a detail in perspective showing one of the coupling pins used at various different places 45 in the coupling connections.

The skis 10, which may be of the standard construction, are provided with the customary raised or intermediate portions 11, having the customary transverse slots 12 for the application of straps in the ordinary use of the skis. As part of the means for coupling the skis into sled formation, I provide posts 13 that may be of any suitable material but are preferably of light metal such as aluminum, flanged and made as light as 50 practical. These posts rest directly on the block

or raised portions 11 of the skis and at their lower ends said posts are provided with clamping straps 14 and 15, the lower ends of which are hooked and adapted to be inserted into the slots or passages 12 of the skis. These connecting straps may be clamped to the posts in different ways but, as shown, they are thus clamped by means of nut-equipped bolts 16 and by a clamping yoke 17, which latter embraces the 5 posts and the straps and is provided with a pivoted clamping lever 18. By the means just described, the posts are very firmly but detachably secured to the skis.

To the up-turned front ends of the skis, metallic toe-clamping plates 19 and 20 are detachably 15 but securely clamped by means of nut-equipped bolts 21, or the like.

On the upper front portions of the posts 13 are coupling lugs 22, and on the upper clamping plates 20, are coupling lugs 23. These lugs 22, 20 and 23 are connected by truss rods or bars made up of telescopic sections 24 and 25. These truss rods or bars are, of course, applied to connect each post to the front end of the co-operating ski. To lock the telescopic sections 24 and 25 25 in the various adjustments, they are shown as provided with perforations 26 through which coupling pins are adapted to be inserted. These coupling pins may take various forms but as here used and in various other places hereinafter 30 noted, they are the type shown in detail in Fig. 7 wherein the numeral 27 indicates the pin proper provided at one end with a head and at its other end with a pivot-like tongue 28. When one of these pins is inserted through the perforations 35 of the telescopically connected sections 24 and 25, and the tongue 28 is turned transversely, accidental removal of the pins will be prevented. The headed ends of the pins 27 are shown as detachably connected to the outer of the telescopic 40 sections by a flexible chain or cord 29. Also, the pins are shown as surrounded by short coiled springs 30 that will be under compression when the pins are inserted and their lock blades turned. At or near their front ends, the sections 25 are 45 shown as provided with pivotally applied lug brackets 31. The lug brackets 31 of the two truss rods are cross connected by a tie rod or bar made up of telescoping sections 32 and 33, the ends of which are pivotally connected to the lug brackets 50 31. The telescopic sections 32 and 33 have perforations 34 through which lock pins may be inserted to hold the skis spread the proper distance; and the pins used may be the pins 27 illustrated in detail in Fig. 7.

The posts 13 are tied together at the rear of the sled by an extensible cross-connected rod or bar made up of telescopic sections 35 and 36 provided with perforations 37 through which pins, such as pins 27 or the like, may be inserted to lock the said rear cross tie bar in the desired arrangement for proper spacing of the skis. At their outer ends the tie rod sections 35 and 36 are directly pivoted to hinge lugs 38 rigidly secured on the posts 13.

The upper ends of the posts 13 are cross-connected by a tie bar structure that includes a steering mechanism and which directly connect the upper ends of post extension rods 39 that are telescoped into the posts 13. These post extensions 39 and the posts 13 have coincident perforations 40 through which lock pins, or the like, such as those shown in Fig. 7, may be inserted to lock the post extensions in different vertical 20 adjustments in respect to their corresponding posts.

At their upper ends the post extensions 39 are rigidly secured to transverse rod or bar-like members that afford handle bars 41 adapted to be gripped by the hands of the person standing on the skis at the rear of the posts, preferably directly on the raised portions 11 of the skis.

The handle bars 41 are preferably tubular and at their inner ends are elbow-like brackets or heads 42 that have trunnion-like stems 43 telescoped into the inner ends of said handle bars and adapted to be locked thereto in different adjustments by lock pins, such as shown in Fig. 7, inserted through coincident perforations 44 in said members 41 and 43, see particularly Fig. 3. The upwardly extended ends of the brackets 42 are connected by a coiled spring 45, the intermediate portion of which is attached to the upper end of a centering bar 46. This centering bar 40 46 is rigidly secured to a coupling sleeve 47 that is telescoped over the trunnion-like ends 48 of coupling heads 49 that are pivotally connected at 50 to the elbow portions of the brackets 42. The lower end of the centering bar 46 is pivoted to the 45 lower ends of a pair of upwardly diverging links 51, the upper ends of which links are pivoted at 52 to the upwardly extended ends or arms of the coupling brackets 42. The links 51, as shown, are made up of laterally spaced straps that 55 brace the coupling sleeve 47.

As an additional feature, I provide a heavy carrying sack 53 made of heavy canvas, leather or other suitable flexible material. This sack is reinforced by transverse straps 54 that extend from corner to corner of the sack and are united to short chains or cables 55 provided with hooked ends adapting them to be detachably applied to coupling rings 56 on the rod sections 25 and to coupling rings 57 on the posts 13. As shown, the 60 rings 56 are applied to sleeves 58 swivelled on the rod sections 25, and the coupling rings 57 are applied to lugs 59 on the posts 13. When the sack 53 is applied, as shown in Fig. 1, it will be so supported above and between the skis that one 65 or more additional persons may ride on the sack. Also, the sack is of such size and formation that detachable portions of the skis, when disconnected and compactly placed together, may be contained within the sack for the purpose of 70 storage or shipment.

The numeral 60 indicates rings applied to sleeves 61 secured on the front ends of the rod sections 25 and to which links a rope or the like may be applied for the purpose of pulling the sled 75 when desired.

The posts 13, somewhat below their upper ends, and on their inner sides, are provided with U-shaped clamps 62; and the rod sections 24 near their lower portions are provided with depending U-shaped spring clamps 63, for purposes 5 which will hereinafter appear.

Operation

Figs. 1 and 2 show the ski sled set up for use as a two runner sled. The operator standing on 10 the skis, preferably on the raised blocks 11, will grip the handle bars 41. By the spring 45 the posts 13 will be normally held in vertical positions so that the sled will then tend to run straight ahead. If the handle bars are pressed 15 toward the left in respect to Fig. 1, or in other words, towards the right of the operator riding on the skis at the rear of the posts, the said posts and the skis will be tilted laterally in a direction to cause the skis to tilt and travel forward but 20 with a drift or trend toward the said direction in which the posts are tilted; but if the handle bars and the posts are tilted in the opposite direction, the tendency of the sled to travel in the opposite direction from that stated will be produced. Obviously by the shifting movements of the handle bars and the posts, the steering of the sled can be controlled. The swivelled couplings 31 and the pivots 38, of course, permit the above noted lateral tilting of the posts, the skis and the 30 brace rods or bars 24—25, while the spacing of the skis is maintained by the cross-connecting rods or bars 32—33, 35—36. The spring 45 readily yields when the handle bars are tilted in the one direction or the other, and under such tilting 35 movements the stems or plungers 48 of coupling heads 49 freely move in the coupling sleeve 47. When lateral pressure is relieved from the handle bars, the spring 45, of course, restores the posts to vertical positions and adjusts the sled for 40 straight ahead travel.

When the sack 53 is applied, as illustrated in Fig. 1, it affords a flexible deck or carrier on which one or more persons may ride; and when the posts are disconnected from the skis and 45 the brace rods, the handle bars and cross-connecting rods are disconnected or uncoupled, and may be slipped into the sack.

If it is desired to use but one ski as a one runner sled, with the posts, handle bars and 50 truss rod or bar connected, the cross-connecting elements 32 and 33 will be separated and turned up against the truss bars to which they are attached and forced into the spring clamps 63 where they will be held; and the cross-connecting elements 35 and 36 will be disconnected and turned upward against the respective posts to which they are attached and engaged and held by the U-shaped clamps 62. Also, to effect this adjustment, the handle bars 41 will be disconnected 60 from and pulled off from the trunnion-like stems 43 leaving only the handle bars attached to the posts. In this way two single runner sleds will be made available. Whether connected as a two runner sled or single runner sleds, the handle 65 bars may be vertically adjusted to suit the operator.

When the sled is adjusted as shown in the drawings, the post extensions 39 will be secured to the posts 13 against rotary movements on a vertical 70 axis and this is an important element in that it keeps the skis from running one ahead of the other. In almost all other respects the connections between the two skis are flexible. The two skis are capable of independent vertical move- 75 .

ments so that the one ski can run over an obstruction without moving the other ski upward; and this is true whether the posts are vertical or tilted in the one direction or the other. To obtain the above rigidity in certain respects and flexibility in other respects noted, it is important that the handle bars or elements 41 be rigidly secured to the post extensions and to the posts. When the posts are tilted in the one direction or the other, there will be an angular movement of the handle bars the one in respect to the other. For example, if the two posts are tilted toward the left in respect to Figs. 1 and 3, the inner end of the left-hand handle bar 41 will be raised, while the inner end of the right-hand handle bar will be lowered, and this will cause the coupling sleeve 47 to assume an oblique position in respect to a horizontal. This movement will take place against the tension of the spring 45 which, acting through the links 51, will cause the right-hand plunger 48 to move outward in the sleeve 47 to prevent cramping of the spring-actuated connections between the two handle bars. Of course, the spring 45 normally holds the posts in vertical positions and will tend to restore the parts to such positions when lateral force is not applied to the handle bars.

A preferred form of the sled has been described, but it will be understood that the same is capable of modifications as to details of construction and arrangement of parts within the scope of the invention herein disclosed and claimed.

What I claim is:

1. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, post extensions rigidly secured and projecting upward from said posts, handle bars on the upper ends of said post extensions, and a yielding spring connection between the inner ends of said handle bars.

2. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, post extensions rigidly secured and projecting upward from said posts, handle bars on the upper ends of said post extensions, a yielding spring connection between the inner ends of said handle bars, said skis at their intermediate portions having strap slots, and said posts at their lower ends having detachably secured metallic clamping straps, the lower ends of which are engageable in the strap slots of said skis.

3. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, post extensions rigidly secured and projecting upward from said posts, handle bars on the upper ends of said post extensions, a yielding spring connection between the inner ends of said handle bars, said post extensions being vertically adjustable in said

posts and said truss rods and cross tie rods being longitudinally adjustable.

4. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, handle bars connected to the upper ends of said posts, and a spring-actuated yielding connection between the inner ends of said handle bars tending to hold the posts in vertical positions.

5. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, handle bars secured to the upper ends of said posts, head brackets secured to the inner ends of said handle bars, plungers pivotally connected to said brackets, a coupling sleeve in which said plungers work slidably, and a spring connecting said head brackets to said coupling sleeve.

6. In a sled of the kind described, a pair of skis, posts secured to and rising from the intermediate portions of the skis, truss rods connecting the upper portions of said posts to the toe portions of said skis, a cross tie rod connecting the front ends of said truss bars, a cross tie bar connecting the lower portions of said posts, handle bars secured to the upper ends of said posts, head brackets secured to the inner ends of said handle bars, plungers pivotally connected to said brackets, a coupling sleeve in which said plungers work slidably, a coupling bar secured to said coupling sleeve, links connected to the lower end of said coupling bar at their lower ends, and at their upper ends to said coupling heads, and a spring intermediately connected to the upper end of said coupling bar and at its ends attached to said coupling heads, said spring tending to hold said posts in vertical positions.

7. The structure defined in claim 6 in which said coupling heads are rigidly secured to the inner ends of said handle bars with freedom for longitudinal adjustments.

8. The structure defined in claim 1 in which said front and rear cross tie bars are longitudinally extensible and are pivotally connected the former to said truss rod, and the latter to said posts.

9. In a sled of the kind described, a pair of skis, posts secured to and rising from the intermediate portions of the skis, truss rods connecting the upper portions of said posts to the toe portions of said skis, a cross tie rod connecting the front ends of said truss bars, and a cross tie bar connecting the lower portions of said posts, and in which structure said cross tie rods and truss bars are longitudinally extensible.

10. In a sled of the kind described, a pair of skis, posts secured to and rising from the intermediate portions of the skis, truss rods connecting the upper portions of said posts to the toe portions of said skis, a cross tie rod connecting the front ends of said truss bars, and a cross tie bar connecting the lower portions of said posts, and in which said skis at their intermediate portions are provided with strap slots and said posts at their lower ends are provided with detachably secured clamping straps with lower ends engageable in the strap slots of said skis.

11. In a sled of the kind described, a pair of skis, posts secured to and rising from the intermediate portions of the skis, truss rods connecting the upper portions of said posts to the toe portions of said skis, a cross tie rod connecting the front ends of said truss bars, and a cross tie bar connecting the lower portions of said posts,

and in which said cross tie rods are made up of detachably connected sections, said truss rods having spring clips adapted to hold the sections of said front cross tie rod, and said posts are provided with spring clips adapted to hold the sections of said rear cross tie rod.

5
NELS SAARI.
